UNITED STATES PATENT OFFICE

JOHN M. WILLARD, OF LOS ANGELES, CALIFORNIA

COLUMN CLAMP

Application filed June 12, 1929. Serial No. 370,376.

This invention relates to a new and novel column clamp particularly adapted for retaining forms used in pouring monolithic columns, piers and the like. The invention particularly relates to a column clamp which is of simple construction and is substantially unitary in character, so that the clamp may be carried, shipped and used as a complete unit without the necessity of employing separate devices or elements therewith.

Clamps of the prior art adapted to be used in retaining forms in position have, as a rule, been very heavy and of rather complicated structure. Such clamps necessitated the use of four or more individual parts or units, and as a result, there has been a great tendency to lose some of the parts during shipping, moving, and during actual construction work. Furthermore, the clamps of the prior art are incapable of forcing the forms around which the clamps are placed into rectangular shape, so that if the forms are slightly trapezoidal instead of rectangular, the common clamps would not force the forms to assume a rectangular position, but instead generally increase the trapezoidal effect.

One of the objects of this invention is to disclose and provide a column clamp composed of a minimum number of units. Another object is to disclose and provide a column clamp which positively forces forms to which said clamp is applied, into rectangular shape.

Another object is to disclose and provide a column clamp, the working parts of said clamps being irremovably made a part of such clamps. Another object is to disclose and provide a clamp which operates to strengthen or square the forms, by a new mode of operation.

A still further object of this invention is to disclose and provide a column clamp which is of light weight.

Other objects, uses and advantages of the invention disclosed, described and embodied herein will become apparent from the following detailed description of one preferred form of the invention. It is to be understood that the description given hereinafter is merely illustrative of one form of the device,

and numerous changes and modifications may be made without departing from the spirit of the invention.

In describing the illustrated form of the device, reference will be had to the appended drawings, in which:

Fig. 1 is a perspective view of a portion of a column clamp embraced by this invention.

Fig. 2 is a plan view showing the column clamp applied around the forms of a column.

In construction work, and particularly in constructing concrete structures, it is customary to erect forms generally made of wood, thin metal or other similar substances, the concrete or other cementitious material being poured within the forms and retained therein until the cementitious material sets the forms, and then removed. During the setting, cementitious materials exert a considerable pressure on the forms, due to the expansion of the materials caused by hydration. Furthermore, when concrete is the cementitious material employed and when wood is used for the forms, the wood absorbs a great deal of moisture, thereby swelling and increasing the disrupted force, which tends to cause a distortion of the columns. The forms as erected, and before they are filled with concrete, are rarely of the precisely desired shape. For example, where a rectangular column is desired, the walls of the forms may not be at right angles to each other.

The column clamp embraced by this invention is particularly adapted to be used with rectangular column forms, the clamp automatically squaring the forms and insuring that the walls of the forms are at right angles to each other. It is to be understood that the clamp of this invention may also be employed with octagonal columns, filler blocks being placed at the corners of a square form so as to produce an octagonal finished column.

A column clamp made in accordance with this invention consists essentially of two pairs of column clamps 1 and 2. Each of said column clamps 1 and 2 is preferably provided with a slotted head 3 and 4, such slotted heads being in engagement with each other. Preferably, the clamping bars 1 and 2 are made of relatively heavy steel bars, adapted

to rest with their edges against the sides of the forms. The column clamps 1 and 2 may be rectangular or they may be provided with a flange so as to increase the bearing surface of the column bars against the forms.

5 The slotted heads 3 and 4 provided in the form clamping bars 1 and 2 may be made in any desired manner. As shown in the drawings, the slotted heads may be formed from straps 5 and 6, each of said straps 5 and 6 forming or including a filler block 7 and 8 having an internal face, such as is indicated at 9, inclined to the longitudinal axis of the form clamping bar of which the filler block 15 is a part.

10 The slotted heads 3 and 4 are in engagement with each other, clamping bar 1 passing through the slotted head 4 and under strap 6, whereas the form clamping bar 2 is 15 slidably received in the slotted head 3 and between the form clamping bar 1 and the strap 5. In this manner it is impossible to separate the clamping bars 1 and 2 from each other, although they may be moved relatively to each other within the limits of the slots or apertures formed in the slotted heads 20 3 and 4, as by the straps 5 and 6.

15 Wedge members 10 and 11 provided with faces 12 and 13 at an angle substantially identical to the inclination of the face 9 made by the blocks 7 and 8, are preferably employed in locking the clamping bars into position around a form such as, for example, a form made of sheathing 14 in which cementitious material is to be poured so as to form 25 a rectangular column.

20 The wedge members 10 and 11 are also provided with faces 15 and 16 which assume a position substantially at right angles with the clamping bars 1 and 2, respectively, when 25 said wedge members 10 and 11 have their opposed faces 12 and 13 in contact with the inclined faces of the slotted heads.

25 In order to prevent the wedges 10 and 11 from being misplaced, protuberances, lugs or pins 17 and 18 are provided in the narrow terminals of the wedge members 10 and 11, said pins, lugs or protuberances 17 and 18 being of such size as to prevent the withdrawal of the wedges 10 and 11 through the slotted heads. Preferably, the length of the slots provided in the heads 3 and 4 is insufficient to allow the wedges 10 and 11 to pass 35 through when moved in the direction of the arrow indicated in Fig. 2. That is, the length of the slot in the head 3 is slightly less than the width of the clamping bar 2 plus the maximum width of the wedge 10.

40 The clamping bars are preferably provided with means for selectively connecting the clamping bars of one pair with the clamping bars of another pair. Such means may comprise a multiplicity of apertures 19 formed in each of said clamping bars 1 and 65 2, the apertures 19 being preferably in stag-

gered relation so as to permit a closer adjustment. Instead of using the apertures 19, other means for connecting the clamping bars to each other may be employed, although preferably, such means are adapted to selectively and pivotally connect the bars.

50 In employing the device embraced by this invention nails or other means of support may be provided exteriorly of the form, such as the sheathing 14, and one of the pairs of clamping bars laid on such support with the faces of the clamping bars 1 and 2 in contact with the sheathing. The wedges are preferably placed in such position as to be almost completely withdrawn from the slotted heads, 55 that is, the narrow portions and protuberances 17 and 18 thereon are preferably closely adjacent to the slotted heads 3 and 4. A similar clamping bar is then placed around the opposed corner of the sheathing with its wedges in withdrawn position, and the form clamping bars 2 of each pair then pivotally connected to each other by means of a pin, bolt or other suitable device 20, inserted through that aperture 19 closest to the heads 60 3 and 4. A similar pin 21 is then used in pivotally connecting the clamping bars 1 together. The wedges 10 and 11 are then driven in on each slotted head, the contact of the wedge members 10 and 11 with the inclined faces of the slotted heads causing the clamping bars 1 and 2 of each pair to assume a position at right angles to each other. The wedges are maintained in the desired 65 position by frictional contact, and any swelling or outward force exerted by the sheathing 14 or by the cementitious material placed therein, merely causes the wedges to more firmly set themselves in position.

70 It will be thus seen that a simple device has been provided, the elements of which are irremovably retained in a coherent unit. The clamping bar firmly strengthens the forms or sheathing and causes the same to assume a positive rectangular position.

75 It is to be understood that numerous changes and modifications may be made in the device described hereinabove without departing from the spirit of the invention, and all such changes and modifications as come within the scope of the appended claims are embraced thereby.

80 I claim:

85 1. A column clamp, comprising two clamping bars provided with slotted heads in adjustable but irremovable engagement with each other, and wedge means carried by said slotted heads adapted to cooperate with a head of one bar and a longitudinal edge of another bar to position said clamping bars substantially at right angles to each other.

90 2. In a column clamp, two clamping bars, each provided with a slotted head, the two bars being inseparably but adjustably connected with each other by interengagement

of said slotted heads, each of said slotted heads including a face inclined to the longitudinal axis of its respective clamping bar, and wedge means adapted to cooperate with the inclined faces of said slotted heads and position said clamping bars substantially at right angles to each other.

3. In a column clamp, two clamping bars, each provided with a slotted head, the two bars being adjustably but inseparably connected with each other by interengagement of said slotted heads, each of said slotted heads including a face inclined at an angle to the longitudinal axis of its respective clamping bar, and wedge means movably retained by said slotted heads and adapted to cooperate with said inclined faces of said heads, and position said clamping bars substantially at right angles to each other.

20 4. A column clamp, comprising two pairs of clamping bars, the clamping bars of each pair being provided with slotted heads in engagement with each other, each of said heads including a face inclined to the longitudinal axis of its respective clamping bar, means carried by each bar of one pair adapted to co-operate with means carried by each bar of the other pair, to selectively and pivotally connect bars of one pair with the bars of another pair, and wedge means adapted to cooperate with said inclined faces of said heads and position clamping bars of each pair substantially at right angles to each other.

25 5. A column clamp comprising two clamping bars, each of said bars being provided with a slotted head, the two bars being adjustably but inseparably connected with each other by interengagement of said slotted heads, and wedge means adapted to cooperate with the head of one bar and the longitudinal edge of another bar to position said clamping bars substantially at right angles to each other.

40 6. In a column clamp, two clamping bars, each provided with a slotted head, the two bars being adjustably but inseparably connected to each other by interengagement of said slotted heads, and wedge means adapted to cooperate with the head of one bar and the longitudinal edge of another bar to position said clamping bars substantially at right angles to each other, each of said wedge means being provided with a transverse extension adapted to movably retain said wedges in said heads.

45 7. In a column clamp, two clamping bars, each provided with a slotted head, the two bars being adjustably but inseparably connected with each other by interengagement of said slotted heads, each of said slotted heads including a fixed face inclined to the longitudinal axis of its respective clamping bar, and wedge means adapted to cooperate with the head of one bar and the longitudinal edge 50 of another bar to position said clamping bars

substantially at right angles to each other, each of said wedge means being provided with a transverse extension adapted to movably retain said wedges in said heads.

8. A column clamp comprising two pairs of clamping bars, each bar being provided with a slotted head, said bars being adjustably but inseparably connected to each other by interengagement of said slotted heads to form pairs of bars, wedge means adapted to cooperate with the head of one bar of a pair and the longitudinal edge of the other bar of the same pair to position said clamping bars of each pair substantially at right angles to each other, and means for selectively connecting the clamping bars of one pair with the bars of another pair.

20 9. A column clamp comprising two pairs of clamping bars, each bar being provided with a slotted head, said bars being adjustably but inseparably connected to each other by interengagement of said slotted heads to form pairs of bars, wedge means adapted to cooperate with the head of one bar of a pair and the longitudinal edge of the other bar of the same pair to position the clamping bars of each pair substantially at right angles to each other, said wedge means being provided with a transverse extension at the small end thereof to movably retain said wedge in said head, and means for selectively connecting the clamping bars of one pair with the bars of another pair.

Signed at Los Angeles, Calif., this 28 day of May, 1929.
